GRIP TENSOR FOR ANTI SLIDING CHAINS

Filed Jan. 18, 1928

FIG. 1.

FIG. 2.

FIG. 3.

FIG. 4.

Adalberto Gualterio Hartung

INVENTOR

BY *Ottolunk*

his ATTORNEY.

UNITED STATES PATENT OFFICE.

ADALBERTO GUALTERIO HARTUNG, OF BUENOS AIRES, ARGENTINA.

GRIP TENSOR FOR ANTI SLIDING CHAINS.

Application filed January 18, 1928. Serial No. 247,554.

The present invention refers to a griptensor for coupling ends and stretching the chains applied on pneumatic tyres of motorcars and other vehicles with the purpose of avoiding the sliding and facilitate its travelling through muddy, boggy and sandy places.

As will further be seen, the grip-tensor, which is the object of the present application, consists essentially of a lever arranged as the 10 sheath of a common penknife and retained at the end of a casing in which has been arranged a cotter or grip stop, destined to retain said lever.

By these means, an easy and rapid grip and 15 opening is obtained.

For the better understanding of this description I accompany drawings, in which:

Fig. I, is the elevation of a common tyre in which an anti-sliding chain has been applied, 20 provided of a griptensor manufactured, according to this invention.

Fig. II, represents an open griptensor.

Fig. III, shows same grip-tensor, closed.

Fig. IV, is a cut according to line A—B of 25 Fig. 3, but with the lever opened, which is also projected closed.

In said drawings, 1 is the common chain, the end of which, *a* is coupled to the casing 2, of the griptensor, while the free end *b* is in 30 combination with closing lever 3, passing it through same, as represented in Fig. II, for carrying it to the position of Fig. III, which is the positon of the grip.

As can be seen, the casing presents a slot 4, 35 which in combination with adjusted part 5, of the lever, forms the hook where the free link *b* is imprisoned.

The cotter 6, is retained in the casing, which presents the broadened part 7, actuated by means of the expansive spring 8, that 40 actuates between the casing and the upper enlargement 9.

In combination with said cotter 6, a slot 10 has been provided in the lever, whose edges 45 11 and 12, have been sharpened to actuate as a wedge when closing the lever and causes the cotter to retire, until the perforation of larger diameter provided at the bottom of the cotter 10, presents itself before it.

This has for its object, to obtain a tight 50 grip, and easy to free, which grip is effected by the fact that it penetrates the broadened part 7, in the broadened perforation of the slot 10, which avoids opening the lever without previously pressing the enlargement or button 9.

The grip is to be so arranged, that the mentioned button 9, remains towards the axis of the wheel to avoid any prominence of the ground pressing it, and cause the aperture of 60 the grip to become ineffective.

For closing the chain, the free link *B* is passed through the link *b*, as can be seen in Fig. I.

In this disposition, the lever rotates, and 65 by said movement the tension of the chain is originated, because the end of said link is caused to reach the point in which the slot 4 is.

When folding the lever into the casing, the 70 lifting and introduction of the cotter in the aperture of the lever, produces the grip.

For opening it, with only pressing the button 9, so as to remove the broadened part and anchor the slot 10, presenting and passing the 75 smaller bolt 6, whose diameter was established according to the passing of the slot.

As has been said, a conical surface fraction has been formed between the broadened part 7 and the bolt 6 which in combination with 80 side end parts, with sharp edges, allows the cotter to be removed and obtain the grip to be automatically effected when pressing the lever.

Having now described and specified the 85 nature of my invention and the manner in which is to be performed, what I claim as my exclusive property and invention, is:

1. Linked tire-chain connecting means, comprising two members pivotally connected 90 together at one end and adapted to close one over the other, and having recesses cooperating in closed position, to receive opposite end-links of the chain.

2. Linked tire-chain connecting means, 95 comprising two members pivotally connected together at one end and adapted to close one over the other, and having recesses cooperating in closed position, to receive opposite end links of the chain, and means for holding the 100 members in closed position.

3. Linked tire-chain connecting means comprising two pivotally connected members, adapted to close one over the other, and having recesses cooperating in closed position, 105 to receive an end link of the chain, the one connecting member having further a slot and the other connecting member having holes adapted to align coaxially with the bottom of the said slot, and a spring pressed cotter 110 bolt having a shoulder to engage one side of the outer member and being slidably axially

within the said holes and the bottom of the said slot, for locking said members in closed position.

4. In a pivotally linked tire-chain connecting means, a U-shaped sheath member, having a slot near its pivotal point and two coaxial holes of different size in the mid-portions of its two sides; a blade member having a recess near its pivotal point to cooperate with the said slot for holding the end link of the chain, and having further in its mid portion an inclined slot with an enlarged end portion; a spring pressed cotter bolt having an enlarged portion and a reduced portion slidable in the two said coaxial holes respectively, the reduced portion of the bolt corresponding to the narrower part of the said inclined slot, and the enlarged portion of the bolt corresponding to the enlarged end portion of the inclined slot.

5. In a pivotally linked tire-chain connecting means, a U-shaped sheath member, having a slot near its pivotal point and two coaxial holes of different size in the mid portions of its two sides; a blade member having a recess near its pivotal point, to cooperate with the said slot for holding the end link of the chain and having further in its mid portion, an inclined slot with a narrower entrance part and an enlarged end portion, the one wall of the slot being beveled; a spring pressed cotter bolt having an enlarged shaft portion and a reduced shaft portion, slideable in the two aforesaid coaxial holes respectively, and a conical mid portion to be engaged by the beveled wall of the said inclined slot for shifting the bolt automatically into the position for locking the blade member within the sheath member.

ADALBERTO GUALTERIO HARTUNG.
